UNITED STATES PATENT OFFICE.

HENRY J. TAYLOR, OF BOSTON, MASSACHUSETTS.

TICKET CLIP-CASE.

1,178,967.

Specification of Letters Patent. Patented Apr. 11, 1916.

Application filed July 6, 1914. Serial No. 849,062.

To all whom it may concern:

Be it known that I, HENRY J. TAYLOR, a citizen of the United States, residing in Boston, in the county of Suffolk and State 5 of Massachusetts, have invented certain new and useful Improvements in Ticket Clip-Cases, of which the following is a specification.

This invention relates to a clip-case for 10 holding tickets and especially for holding a strip of tickets of the form in which street car tickets or the like are generally put up.

One of the main objects of the invention is to provide a case that will hold a strip of 15 tickets one fastened to the other, the tickets being defined from one another by a line of perforations, which case will permit the withdrawal of one ticket at a time.

Other objects of the invention are to provide 20 a ticket clip-case which can be conveniently carried in a vest pocket or the like; which can be conveniently and firmly held in one hand while the fingers of that hand remove the ticket; which can be made at 25 low cost; and which is simple in operation, that is in the removal of the ticket, and in supplying the case with tickets.

A particular feature of the invention is 30 that the device is a one-piece article made of sheet metal.

Other features, capabilities and advantages of the invention will appear from the subjoined detailed description of one specific embodiment thereof illustrated in the accompanying drawing in which—

Figure 1 is a plan of the device shown in 40 closed position. Fig. 2 is an elevation of the same. Fig. 3 is an axial section of the same on the line 3—3 of Fig. 1 showing the edge 45 of the strip of tickets. Fig. 4 is an elevation of the same in open position. Fig. 5 is a cross section of the same on the line 5—5 of Fig. 2. Fig. 6 is a diagrammatic elevation of a strip of tickets, the dotted lines showing 50 the course through which a portion of the strip will bend when a ticket is removed from the case. Fig. 7 is an enlarged detail fragmental view in section showing the means for locking the case in closed position; and Fig. 8 is a plan of the stamped 55 blank before bending into finished form.

In the embodiment shown, a clip case formed of one piece of metal has an upper plane plate portion 1 and a lower plane plate 60 portion 2 which are connected to one another by a loop connection 3, the loop being re-

silient and in normal position maintaining the plate portions 1 and 2 spaced from one another in open position as shown in Fig. 4, and being under tension when in closed position as shown in Fig. 2. The loop 3 bulges 60 outward from the plate portions 1 and 2. For the dual purpose of providing an increased gripping surface and providing a loop with the greatest resilient working surface possible, the sheet metal is broader at 65 the loop than at the plate portions 1 and 2, it increasing in width as it recedes from the plate portions 1 and 2 and being broadest at the crest of the loop, the edge of the metal 70 sheet however, forming one continuous uninterrupted edge on each side of the loop.

The lower plate 2 is bent up on its front 75 free end to form a vertical member 4 perpendicular to the main body of the plate 2 and then again bent at right angles to said vertical member 4 to form the horizontal member 5 which extends out from the plate portion 2 and forms one of the surfaces over which the ticket being removed from the case 80 passes.

On each lateral edge of the plate portion 2 is provided a wall member 7 bent up from the plate portion 2 and extending toward the plate portion 1, which wall member 85 comprises a low wall member 8 starting near the vertical member 4 and extending back about half the length of the plate 2 where it is continued by the high wall member 9 which extends back substantially the 90 remaining half of the plate portion 2. This high wall member 9 has a punched-out lug 10 near its forward end and a raised elongated portion 11 extending practically the 95 remaining length of the wall member 9. Both the lugs 10 and raised portions 11 extend outward of the case.

The front end of the upper plate 1 terminates a little short of the end of the horizontal member 5, this front end extending 100 adjacent to and parallel to the horizontal member 5. At each lateral edge of the plate portion 1 is provided a wall 12 extending toward the plate portion 2 and having at its middle an extended portion 13 provided 105 with an opening 14 which is adapted to engage the lug 10 on the plate portion 2 to lock the two plate portions together in closed position. To permit the free bulging of the tickets near the front end of the case 110 when one is being removed, the plate portion 2 is looped outward at 15, which loop

continues into the vertical member 4. At the front end of the plate portion 1 and also of the horizontal member 5, there is provided a recess 16 to facilitate gripping the 5 ticket being fed from the case.

In the use of the device a strip of tickets 17 is folded along the perforations defining them and packed together as shown in Figs. 3 and 6, then placed into the case and onto 10 the plate portion 2, the free end of one of the end tickets resting on the horizontal portion 5, then the plate portion pressed down onto the plate portion 2 so that its openings 14 engage the lugs 10 of the plate portion 2, whereby the plate portions are locked parallel to one another in closed position with the strip of tickets therebetween, the space between the front end of the plate portion 1 and the horizontal portion 5 forming 15 the outlet for the tickets to be removed. When the supply of tickets is exhausted and it is desired to refill the case, the case is opened by pressing the elongated raised portions 11 toward one another, whereupon the 20 lugs 10 are removed out of the openings 14 of the plate portion 1, and the tension of the loop portion 3 is free to snap up the plate portion 1, removing the same from the plate portion 2, so that access is had to the 25 inside of the case and a fresh supply of tickets can be placed therein.

In Fig. 8 is shown a blank 18 before being bent and formed into the finished case. The simplicity of construction is clearly 35 illustrated in this figure, the several parts of the device being designated with the same reference characters as are used to designate corresponding parts in Figs. 1 to 7 inclusive.

It is obvious that various changes and 40 modifications may be made in the details of construction without departing from the general scope of the invention.

I claim:

1. A ticket clip-case having two plate portions adjacent to one another in closed position, resilient means connecting the plate portions to one another and normally maintaining the same in open position, lateral extensions in said plate portions to interlock 50 with one another to lock said plate portions to one another in closed position, and disengaging means on one of said plate portions adapted to be pressed inwardly to disengage said lateral extensions from one another so that said resilient means may snap the plate portions from one another into open position.

2. A ticket clip-case comprising a strip of metal forming two plate portions adjacent 55 to one another in closed position, a resilient loop connecting the two plate portions to one another and normally maintaining the same in open position, means on said plate portions for locking said plate portions to one another in closed position, and disengaging

means on one of said plate portions adapted to be pressed inwardly to disengage said plate portions from one another so that the resilient loop may snap the plate portions from one another into open position. 70

3. A metal clip-case comprising a strip of metal forming two plate portions adjacent to one another in closed position, a resilient loop portion connecting the two plate portions to one another and normally maintaining the same in open position, one of said plate portions having a raised member at its free end between which raised member and the other plate portion the tickets are fed from the case, side walls on the upper 80 plate portion provided with openings, side walls on the lower plate portion provided with punched-out lugs adapted to engage the openings in the side walls of said upper plate portion when the plate portions are 85 in closed position and to lock the two plate portions in such closed position in which position there will be formed a narrow slit between said raised member of one plate portion and the other plate portion. 90

4. A metal clip-case comprising a strip of metal forming two plate portions adjacent to one another in closed position, a resilient loop portion connecting the two plate portions to one another and normally maintaining the same in open position, side walls on the upper plate portion provided with openings, side walls on the lower plate portion provided with punched-out lugs adapted to engage the openings in the side 100 walls of said upper plate portion when the plate portions are in closed position and thereby lock the two plate portions in such closed position, and elongated raised portions on the side walls of said lower portion 105 which are adapted to be engaged and pressed inwardly to press in the side walls of the lower plate portion thereby to remove the lugs from the openings of the upper plate portion and to permit the resilient 110 loop to snap the upper plate portion away from the lower plate portion.

5. The combination with a clip case comprising a strip of metal forming two plate portions adjacent to one another in closed 115 position, connected to one another at one end, and forming an outlet with one another at the other end to permit the removal of tickets from the case, of a strip of tickets secured to one another and defined from one 120 another by perforations, folded along said perforations, and packed in said case with the free end of one of the end tickets extending through said outlet, and an outwardly bulging portion formed in the lower 125 plate portion near the outlet, to permit the bulging of the tickets at such end of the case when a ticket is removed.

6. A one-piece sheet metal blank for a ticket clip-case having two similarly formed 130

plate portions, an intermediate enlarged portion which forms a resilient loop in finished form of the clip-case, the plate portions having lateral extensions which are 5 formed into interlocking members for locking the plate portions in closed position when in finished form, and disengaging means on one of said plate portions adapted to be pressed inwardly to disengage said 10 lateral extensions from one another so that the resilient loop may snap the plate portions from one another into open position.

7. A ticket clip-case comprising a strip of metal forming two plate portions adjacent to one another in closed position, a 15 resilient loop connecting the two plate portions to one another and normally maintain-

ing the same in open position, lateral extensions on the lower plate portion, lateral extensions on the upper plate portion adapted 20 to receive and temporarily interlock with the lateral extensions on the lower plate portion, and disengaging means on the lower portion adapted to be pressed inwardly to release the lateral extensions of the lower 25 plate portion from the lateral extensions of the upper plate portion so that the resilient loop may snap the upper plate portion away from the lower plate portion.

HENRY J. TAYLOR.
